ARCHER'S ARM

Richard R. Carmardella, Payne St., Elmsford, N.Y.

Filed Nov. 3, 1958, Ser. No. 771,264

3 Claims. (Cl. 124—23)

This invention relates to sporting goods and, more particularly, to archery equipment.

It is sometimes difficult, if not impossible, for some individuals to draw the bow string of a bow and retain it in a tensioned firing position for any length of time. However, such is ordinarily necessary for target practice and for game hunting in order to secure the proper aim and opportunity to fire upon the target. It is therefore an object of the present invention to provide an accessory for an archery bow that will enable all persons to withdraw the bow string and secure it in the tensioned position for a substantially long period of time until proper aim is taken.

Another object of the present invention is to provide an accessory for an archery bow that will improve the aim and will more quickly improve the skill of the archer.

Still another object of the present invention is to provide an archery accessory of the type described that can be adjustably mounted upon any desired bow in a simple and convenient manner.

All of the foregoing and still further objects and advantages of this invention will become apparent from a study of the following specification, taken in connection with the accompanying drawing, wherein:

Figure 1 is a side elevational view of an archery bow made in accordance with the present invention, equipped with an accessory of the type described in operative use;

Figure 2 is an enlarged fragmentary cross sectional view taken along line 2—2 of Figure 1;

Figure 3 is an enlarged fragmentary perspective view, with parts broken away, of a clamp element forming a part of the present invention;

Figure 4 is an exploded perspective view of certain parts of the apparatus shown in Figure 1, showing a handle assembly made in accordance with one form of the present invention;

Figure 5 is a transverse cross sectional view taken along line 5—5 of an assembled handle, such as that shown in Figure 4; and

Figure 6 is a fragmentary longitudinal cross sectional view of a slightly modified form of handle construction.

Referring now to the drawing, and more particularly to Figures 1 to 5 thereof, an archery bow assembly 10 made in accordance with the present invention is shown to include a main bow 12 having a bow string 14 secured at opposite ends to opposite ends of the bow 12. The position of the bow illustrated in broken lines in Figure 1 shows the position of the parts with the bow drawn, whereas the full lines illustrate the advanced position of the parts after firing of the arrow. The mid portion of the bow 12 defines a hand grip 15, all in a conventional manner. However, the accessory made in accordance with the present invention further includes a pair of substantially rigid rods 16, each of which is provided with a spring clamp element 18 that is selec-

2

tively secured to any one of the longitudinally spaced apart internally threaded bores 22, such as by a screw 20. A resilient sleeve 24 encloses the bow engaging portion of the spring clamp 18 so as to prevent scratching of the bow 12 in actual use.

The opposite rear terminal ends of the rigid rods 16 include spherical ball members 26 that are receivable within sockets 28 defined by the halves 30 of a handle assembly when such handle halves are secured together, such as by screws 31. As a result, the spherical ends 26 of the rigid rods 16 are effectively locked in place as a single assembly.

With reference now to Figure 6 of the drawing, a slightly modified form of construction 32 is shown wherein the rear ends of the rigid rods 34 are received within sockets 36 adjacent to the opposite ends of a rigid composite handle member 38, and secured thereto, such as by screws 40.

In actual use, the accessory is clamped to the bow 12 with the spring clamp 18 in a suitable position to provide the proper extent of rearward movement of the bow string 14. With the clamps in the position shown in the drawing, a minimum effort is required to retract the bow string 14 to the handle portion of the assembly. However, by moving the spring clamps 18 further out toward the adjacent end of the rigid rods, the amount of pull necessary to retract the draw string 14 to the handle member is increased. As a result, this device can be adjusted to accommodate archers of all ages and with varying degrees of skill and experience.

While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

1. An arrow shooter comprising, in combination, a bow having a hand grip intermediate the opposite ends thereof, a bow string for driving an arrow secured at opposite ends to said opposite ends of said bow, an arm assembly secured to said bow for securing said bow string in a retracted position with said bow under tension to support an arrow in a firing position, said arm assembly comprising a pair of rigid rods, clamps securing said rods at one end to said bow each adjacent to an opposite end of said hand grip, and a handle secured to the opposite ends of both of said rigid rods, said clamps comprising spring clamps, said one end of each of said rods defining a plurality of longitudinal spaced apart threaded bores, and a screw threadedly securing each one of said clamps in a selected adjusted position along the length of each said rod.

2. An arrow shooter as set forth in claim 1, wherein said handle comprises a pair of handle halves each defining a spherical socket at each end, and said opposite end of each of said rods defining a spherical portion receivable within communicating sockets of said handle halves, and screws securing said handle halves together.

3. An arrow shooter as set forth in claim 1, wherein said handle comprises a solid block defining a pair of sockets on one side each adjacent to one end thereof, and said opposite ends of said rods being secured within said sockets.
